DESIGN FOR A WHEEL BALANCING WEIGHT

Paul F. Hatch, Ypsilanti, and Malcolm J. Hume,
Ann Arbor, Mich., assignors to Harley C. Loney
Company, Detroit, Mich., a corporation of
Michigan

Application June 22, 1938, Serial No. 77,984

Term of patent 7 years

To all whom it may concern:

Be it known that we, Paul F. Hatch and Malcolm J. Hume, citizens of the United States, residing at Ypsilanti, in the county of Washtenaw, State of Michigan, and at Ann Arbor, in the county of Washtenaw, State of Michigan, respectively, have invented a new, original, and ornamental Design for Wheel Balancing Weights, of which the following is a specification, reference being had to the accompanying drawing forming a part thereof.

Fig. 1 is a perspective view of a wheel balancing weight showing our new design,

Fig. 2 is a rear elevation thereof,
Fig. 3 is a front elevation thereof, and
Fig. 4 is an end view thereof.
The dominant features of our design are indicated by solid black lines in the drawing.

We claim:

The ornamental design for a wheel balancing weight, as shown and described.

PAUL F. HATCH.
MALCOLM J. HUME.
